HAIR NET FOR BOBBED HAIR STYLES

Arthur M. Herschensohn, Scarsdale, N. Y.

Application June 10, 1950, Serial No. 167,294

1 Claim. (Cl. 132—49)

1

The present invention relates to ladies' hair nets.

The principal object of this invention is to provide a hair net of novel and improved construction, which is specially suited for bobbed hair coiffures.

In most styles of bobbed hair arrangements, the bottom zone of the hair-do is comprised of the curled ends of the hair, the top of the head is the zone where the hair is substantially straight and intermediate such mentioned zones is the zone where the hair is waved. My improved hair net is so constructed, that the hair in the curled region is held securely against the head, thus fixing the waved hair portions against downward movement which would unravel the wave and holding the hair in the curled region in the arranged style and format. The net also offers the required stability of position of the hair in the waved region or zone where the intermediate portions of the hair are in waved formation. The crown of the net, covering the straight hair zone, is ordinary. The details of structure of my improved net will now be set forth.

In the accompanying drawings forming part of this specification, similar characters of reference indicate corresponding parts in all the views.

Fig. 1 is a pictorial view of a hair net embodying the teachings of this invention, shown on the head of a wearer.

Fig. 2 shows the back of the head of a lady whose bobbed hair is arranged in fundamental style which is the basis of most hair-dos for short hair. In this view are indicated the mentioned zones of straight hair, waved hair and curled hair.

Fig. 3 is a fragmentary portion of my improved net shown in plan; the bottom line in this view being the rim of the net and the top portion being of the crown.

In the drawings, the zone around the head 15, indicated by the letter A is where the hair is substantially straight. In zone B, the hair is waved and in the zone C, the hair is curled and includes the hair ends.

The crown portion 16 of the hair net 14, is of an extent to cover the zone A. The rim band portion 17 of the hair net is to cover the zone C and the intermediate net portion 18 is to cover the zone B of the wearer's head 15. Net portion 16 is of rather coarse mesh. The net portion 17 is of relatively fine mesh, while the mesh of the net portion 18 is coarser than of portion 17 and finer than that of net portion 16. As a practical example, net portion 16 may be of $\frac{3}{8}$ inch netting, portion 18 of $\frac{1}{4}$ inch netting and portion 17 of $\frac{1}{8}$ inch netting. The net portion 18 is preferably a little narrower than the net portion 17, and their respective widths may be two and two

2

and one-half inches. I find these dimensions really suitable for the purposes intended.

An elastic 21 is around the net's rim. Another elastic 19 is on the junction line of net portions 17 and 18, and at least one elastic 20 is around the net on portion 17, intermediate the elastics 19 and 21, preferably midway. For the dimensions given, I find one such intermediate elastic 20 sufficient. The manner of weaving in the elastics is well known in this art and therefore needs no further explanation.

Net portion 16 holds the hair it covers in ordinary manner as is usual in hair net function. Net portion 18 being of a less coarser mesh, better holds the hair which is waved in zone B. The elastics 19, 20 and 21 being tensed when the net is worn, securely holds and positions the curled hair in the zone C with the aid of the fine mesh netting of the net portion 17, against the head of the wearer, where the very ends of the hairs are held against movement by such fine mesh acted on by the tensed elastics.

This invention is capable of numerous forms and various applications without departing from the essential features herein disclosed. It is therefore intended and desired that the embodiment shown herein be deemed illustrative and not restrictive and that the patent shall cover all patentable novelty herein set forth; reference being had to the following claim rather than to the specific description herein to indicate the scope of this invention.

I claim:

A hair net comprising a crown portion, a rim band portion and intermediate band portion connecting the rim and crown portions; the crown portion being of relatively coarse mesh netting, the rim band portion of relatively fine mesh netting and the immediate portion of netting whose mesh is coarser than that of the rim band portion and finer than that of the crown portion and including elastics woven in respectively around the rim of the net, around the junction of the rim and intermediate portions and around the rim band portion intermediate the other elastics.

ARTHUR M. HERSCHENSOHN.
